UNITED STATES PATENT OFFICE.

JOHN NIEDER, OF NEWARK, NEW JERSEY.

DESIGN FOR LEATHER FABRIC.

SPECIFICATION forming part of Design No. 32,415, dated March 27, 1900.

Application filed February 24, 1900. Serial No. 6,421. Term of patent 3½ years.

To all whom it may concern:

Be it known that I, JOHN NIEDER, a citizen of the United States, residing at Newark, in the county of Essex and State of New Jersey, have invented and produced a new and original Design for Leather Fabric, of which the following is a specification, referring to the accompanying drawings, forming a part thereof.

A indicates a piece of leather fabric having depressed veins *a* of various twists and turns and which are not parallel, but simply have a general trend longitudinally of the leather. Corresponding raised veins *b* are arranged at the opposite side of the leather. Fainter and less-pronounced depressions or cavities *c* are located between the veins *a*, while faint cross-veins *d* traverse the veins *a*.

Figure 1 is a plan view of a piece of leather fabric embodying my design. Fig. 2 is a longitudinal section on line 2 2, Fig. 1; and Fig. 3 is a transverse section on line 3 3, Fig. 1.

The leading features of my design are a series of depressed veins of various twists and turns, which are not parallel, but all of which extend in a general longitudinal direction, corresponding raised veins being formed in the opposite side of the piece of leather, and fainter and less-pronounced depressions or cavities, the whole having a generally-mottled appearance.

What I claim is—

The design for leather fabric, herein shown and described.

In testimony that I claim the foregoing as my invention I have signed my name in presence of two subscribing witnesses.

JOHN NIEDER.
